FOOD LIFTING TONGS

Eugene E. Davis, 2726 W. 33rd St., Erie, Pa. 16506

Filed Oct. 11, 1973, Ser. No. 405,312

Term of patent 14 years

Int. Cl. D7—06, 08

U.S. Cl. D7—105

FIG. 1 is a top perspective view of the food lifting tongs showing my new design.

FIG. 2 is an end elevation view from the right of FIG. 1.
FIG. 3 is a top plan view thereof.

The bottom and side opposite those shown are similar to those shown in FIGS. 1 and 3.

I claim:

The ornamental design for food lifting tongs, as shown and described.
